US00D801987S

(12) **United States Design Patent** (10) Patent No.: **US D801,987 S**
(45) Date of Patent: **** Nov. 7, 2017**

(54) **DISPLAY SCREEN WITH GRAPHICAL USER INTERFACE**

(71) Applicant: **Google Inc.**, Mountain View, CA (US)

(72) Inventors: **Dorington Little**, San Francisco, CA (US); **Michelle Chen**, San Francisco, CA (US); **Marcus Lowe**, San Francisco, CA (US)

(73) Assignee: **Google Inc.**, Mountain View, CA (US)

(**) Term: **15 Years**

(21) Appl. No.: **29/573,324**

(22) Filed: **Aug. 4, 2016**

(51) LOC (10) Cl. **14-04**

(52) U.S. Cl.

USPC **D14/485**; D14/492

(58) **Field of Classification Search**

USPC D14/485-495

CPC G06F 3/04817; G06F 3/0482

See application file for complete search history.

(57) **CLAIM**

The ornamental design for display screen with graphical user interface, as shown and described.

DESCRIPTION

The FIGURE is a view of a display screen with graphical user interface, showing our new design.

The broken lines of uneven length show the display screen and form no part of the claimed design. The broken lines of even length shown in the drawing illustrate portions of the display screen with graphical user interface that form no part of the claimed design.
